UNITED STATES PATENT OFFICE

ERNEST DAVIS, OF SYRACUSE, NEW YORK, ASSIGNOR TO THE PROSPERITY COMPANY INC., OF SYRACUSE, NEW YORK, A CORPORATION OF NEW YORK

PRESSING MACHINE

Application filed August 21, 1928. Serial No. 301,005.

This invention relates to pressing machines, as garment and laundry pressing machines, and has for its object a particularly simple, efficient and compact actuating mechanism by which the press is closed and heavy pressure is applied with minimum expenditure of power and also a particularly simple and efficient mechanism by which the pressure delivered by the machine, when closed, can be instantly adjusted to suit the conditions and it further has for its object a particularly simple and efficient mechanism by which the control of the pressure adjusting means is dependent upon the operation of the operator-operated members which control the closing of the press.

The invention consists in the novel features and in the combinations and constructions hereinafter set forth and claimed.

In describing this invention reference is had to the accompanying drawings in which like characters represent corresponding parts in all the views.

Figure 1 is a side elevation, partly in section, of a machine embodying my invention.

Figure 2 is a fragmentary plan view of the parts seen in Figure 1.

Figure 3 is a partly diagrammatic view illustrating the operation of the actuating mechanism and the controls therefor and for the pressure adjusting means.

Figure 4 is an enlarged sectional view through the pressure adjusting means.

Figure 5 is a detail view of the carrier for the adjustable motion transmitting member of the actuating mechanism.

Figure 6 is a fragmentary view illustrating a modified form of the pressure adjusting means.

Figure 7 is a side elevation, partly in section, of a machine provided with another form of pressure adjusting means.

Figure 8 is a sectional view taken approximately on line 8—8, Figure 6.

Figure 9 is an elevation of a complete machine provided with a standard.

Figure 10 is a view similar to Figure 9 showing the machine as placed upon a bench.

This pressing machine comprises, gener-

ally, cooperating pressing elements, one of which is movable toward and from the other, mechanism for actuating the movable element, this mechanism including a motion transmitting member and a motor or power means connected to said member, and pressure adjusting means, the motion transmitting member acting or thrusting in opposite directions on the movable element and on the pressure adjusting means during the closing of the press. Preferably there is an interlock between the manual means which control the operation of the motor to close the press and the manual control by which the pressure of the pressure adjusting means is increased at the will of the operator so that the pressure adjusting means can only be operated when the press is closed.

Some of the foregoing features may be omitted.

In the illustrated embodiment of the invention, the cooperating pressing elements are a buck 1 and a head 2 movable toward and from the buck, the buck 1 being mounted upon a bracket or goose neck 3 which is supported upon a base 4, the latter being hollow and housing the greater part of the actuating mechanism.

The actuating mechanism comprises a lever 5 pivoted between its ends at 6 to the base in the rear of the buck, this lever being usually termed a yoke lever and carrying the head 2 at its front end. In addition to the yoke lever, the actuating mechanism comprises a motion transmitting member 7, a fluid operated motor, as a cylinder 8, having a piston 9 movable therein and connections as a link or connecting rod 10 between the piston and the motion transmitting member 7.

The motion transmitting member coacts directly with the rear arm of the lever 5, and these two parts 5 and 7 are provided with a coacting cam and follower so arranged as to close the press during the movement of the member 7 in one direction, and to open the press during movement of the member 7 in the opposite direction, the cam extend-

ing in a general direction radially relatively to the axis of the lever 5.

The motion transmitting member 7 is here shown as a lever arranged beneath and extending at an angle to the lever 5 and as pivoted at its lower end as hereinafter set forth. The upper end of the lever 5 is provided with a follower 11 movable along a cam slot 12 formed in the rear arm of the yoke lever 5. The yoke lever 5 is usually formed double with a cam slot in each side or branch thereof and the lever 7 extends between the branches of the yoke lever and has followers 11 on opposite sides thereof movable in the cam slots 12.

The lever 7 is also formed with bifurcated arms 13 arranged at an angle thereto and the connecting rod is pivoted at 14 between said arms. The piston 9 is single acting.

20 The press is opened when the pressure in the cylinder is released, by countersprings 15 connected at their front ends at 16 to the base 4 within the hollow cavity thereof and at their rear ends at 17 to brackets 18 projecting from the lever 7.

The cylinder 8 and the springs 15 are arranged in horizontal position within the hollow base so that the pressing machine is a unit which can be set upon a standard or a bench or any other support. This feature, however, in itself forms no part of this invention.

35 The lever 7 is pivoted at its lower end to a carrier which is shiftable to adjust the pressure between the elements 1 and 2 or the pressure delivered by the head 2. The shifting of the carrier varies the initial or starting position of the head 2 when in open position and also the shifting of the carrier, when the 40 press is closed, applies additional thrust or pressure to the lever 7 which, acting in conjunction with the pressure on the piston 9, increases or raises the pressure delivered by the head 2.

45 The carrier 19 is here shown as a yoke pivoted at 20 to a block 21 within the base and carrying and eccentric pin or crack bearing 22 on which the lower end of the lever 7 is mounted and as having arms 23 extending from its axis, said arms being arranged at an acute angle to the arms of the yoke portion which carry the crank bearing 22. The two arms 23 coat with the pressure adjusting means to be presently described.

55 In the preferred form of my invention, the pressure adjusting means is fluid operated and consists of a pair of cylinders 24 for receiving a hydraulic fluid as oil and a piston 25 in each of the cylinders. Each piston has its rod 26 connected to one of the arms 23 of the carrier 19.

During the movement of the pistons 9 on their out stroke, the thrust of the motion transmitting member or lever 7 is in opposite directions against the yoke lever 5 and the

carrier 19 and hence through the carrier and piston 26 against the hydraulic fluid or oil in the cylinders 24. A suitable gage 27 is connected by a pipe 28 to one of the cylinders 24 to indicate the pressure.

70 A supply chamber or reservoir 29 is connected to both of the cylinders 24 through pipes 30 having check valves 31 therein and in order to relieve the pressure in the cylinders 24, a by-pass 32 is provided around each 75 check valve, each by-pass having a normally closed manually operable valve 33 therein.

The means for adjusting the resisting pressure in the cylinder comprises a manually operable valve for controlling the flow of a fluid under pressure, as air, to the upper surface of the liquid within the reservoir 29 and preferably in order that the carrier 19 may be shifted only when the press is closed, the 80 manual control for the air passing through the reservoir chamber 29 to boost the pressure therein is interlocked with a manual control for the cylinder 8.

85 The manual control for the cylinder 8 comprises a valve casing 34, Figure 3, having a 90 spring pressed normally closed intake valve 35 and a normally open exhaust valve 36 therein, a manual as a push button 37, the motion of which is transmitted through levers 38, 39 to the stem 40 of the exhaust valve. 95 The intake and exhaust valves 35, 36 are connected by a stem 41 so that they act as a unit. The exhaust valve controls an exhaust passage 42. The intake end of the valve casing 34 is connected by a suitable pipe 44 to a supply tank. The valve casing is connected between its ends by a pipe 45 to a coupling 46 on the cylinder and communicating with the intake port 47 in the head of the cylinder. 100

105 The machine here shown also includes a dual manual control requiring both hands of the operator to be used to close the press, the other manual operating a normally open exhaust valve.

110 48 designates the casing of said exhaust valve. 49 is the normally open exhaust valve therein, which is operable by means, as a push button 50, similar to the push button 37 and levers 51, 52, similar to the levers 38, 39. 115 The valve casing 48 is connected by a pipe 53 to the coupling 46. Neither the valve construction nor the two hand control per se, forms part of this invention.

115 Depression of the push buttons 37, 50 permits the air to flow from the supply pipe 44 through the valve casing 34, pipe 45 to the cylinder 8 to actuate the piston 9 therein on its power stroke. If the push button 50 is not depressed, the air will pass from the coupling 46 through the pipe 53, valve casing 48 and out through the exhaust passage 54 controlled by the exhaust valve 49. Hence, the press can not be closed unless both push buttons are depressed.

Means, the construction of which forms no part of this invention, are also provided for holding the valves in their operated position, this means being pressure operated and including diaphragm chambers 55, 56 having diaphragms 57, 58 therein respectively acting on sliding stems 59, 60 which act on the levers 39 and 52 respectively. The pressure sides of the diaphragm chambers are connected by pipes 61, 62 to a coupling 63 on the side of the cylinder, which coupling is connected by a pipe 64 to a coupling 65 having a port 66 opening into the cylinder and arranged to be uncovered by the piston when the piston is well on its out stroke.

Obviously, when the port 66 is uncovered by the piston, the pressure will pass from the cylinder back through the pipes 61, 62 to the diaphragm chambers, operating the diaphragms therein and hence acting on the levers 39, 52 to hold them and the valves operated thereby in their operated positions.

To open the press, the pressure in the diaphragm chambers is released so that the valves are free to return to their normal position and the air to exhaust from the cylinder back through the port 47, pipes 45, 53.

The releasing means comprises a valve casing 67 having a normally closed exhaust valve 68 therein, the casing being connected by a pipe 69 to any pipe connected to the diaphragm chambers here shown as the pipe 61. The exhaust valve 68 is held closed by a spring 70 and is opened against the action of the spring by a trip lever 71 acting upon the stem of the exhaust valve 68.

The means for controlling the flow of air to the pressure adjusting means or the reservoir chamber 29 thereof comprises a valve mechanism similar to that for controlling the flow of motive fluid to and from the cylinder, that is, it comprises a valve casing 72 having a spring pressed normally closed intake valve 73 therein and a normally open exhaust valve 74, these valves being connected together by a stem 75 and being operated by a push button 76.

The intake end of the valve casing 72 is connected by a pipe 77 to any pipe communicating with the feed line 44 and connected to the chamber 29 by a pipe 79 leading from the valve casing 72 from between the ends thereof and opening into the top of the chamber 29. The pipe 79 has a check valve 80 therein for preventing the back flow of fluid from the chamber 29 when the push button 76 is released. When the push button is released, the valves 73 and 74 operated thereby return to their normal position. In order that the air pressure may be applied, and hence the pressure boosted only when the press is closed, an interlock is provided between the valves operated by the manuals or push buttons 37 or 50 and the valves operated by the push button 76 and this interlock

consists of connecting the pipe 77 to one of the pipes which controls the holding of the valves operated by the push button 37, 50 in their operated position, and as here shown, the pipe 77 is connected to the pipe 62 leading to the diaphragm chamber 58, so that effective air pressure can not flow to the valve casing 72 even though the valve 73 is open until the diaphragms 57, 58 have been operated to lock the valves 35, 40 and 49 in their operated position, this event not occurring until the press is closed.

In order to automatically adjust the pressure, means is provided for transferring the pressure from the cylinder 8 to the chamber or cylinder 29 under certain conditions, and as here illustrated, the cylinder 8 is connected to the cylinder or chamber 29 by a pipe 81 connected at one end to the top of the chamber of cylinder 29, and at its other end to a coupling 82 on the cylinder 8, the coupling having a port opening into the cylinder and located in position to be uncovered by the piston when the piston travels beyond its normal power stroke, as when the padding settles, or the work being operated on, is thinner than the work previously operated on.

In the normal operation, the piston 9 travels in the cylinder 8 far enough to uncover the port 66 to effect the locking of the control valves, and stops on its power stroke between the port 65 and coupling 82. If, due to conditions, the piston 8 travels far enough to uncover the port in the coupling 82, the pressure will be transferred from the cylinder 8 to the chamber of cylinder 29 and boost the pressure if the operator has not previously boosted the pressure by depressing the push button 76. The check valve 80 in the pipe 79 prevents the passage of air out through the pipe 79 when the piston 8 travels far enough to uncover the port in the coupling 82. The pipe 81 and coupling 82 may be omitted, or the pipe 79 and associated valve mechanism operated by the push button 76, may be omitted, or both of these pressure adjusting means may be used in one machine as illustrated.

In operation, the operator depresses both push buttons 37 and 50 to close the press and as the press comes into closed position, the operator by looking at the gage 27 can determine whether the pressure is up to the point required, and if not, by merely pressing the push button 76 can boost the pressure in the cylinder 24 causing it to actuate the carrier 19 about its pivot and hence, thrust the lever 7 endwise against the rear arm of the yoke 5 with increased pressure. In the event the operator does not keep the pressure adjusted by depressing the push button 76, the pressure will be automatically adjusted when the piston 9 travels far enough to uncover the port in the coupling 82.

As seen in Figure 6, the arm 23 of the carrier may be adjusted to shift the carrier to in-

crease or decrease the pressure by means of a hand-wheel 83 serving to turn a screw 84 threading through a nut 85 carried at the front end of the arm 23.

5. What I claim is:

1. A pressing machine comprising a hol-

low base, a buck mounted on the base, a head movable toward and from the buck, a lever pivoted intermediate of its ends to the base

10 in the rear of the buck and carrying the head at its front end, a second lever pivoted to the base beneath the rear arm of the former lever, the second lever and the rear arm of the lever having coacting cam and follower elements

15 arranged to effect the opening and closing of the press, a motor mounted within the base beneath the buck, connections between the motor and the second lever, and means for controlling the operation of the motor.

20 2. A pressing machine comprising cooper-

ating pressing elements, one of which is mov-

able toward and from the other, actuating mechanism for the movable element includ-

25 ing two parts, one being a lever carry-

ing the movable element and the second part coacting with the lever to move it, one of

30 said parts having a cam and the other a follower engaging the cam, the cam being shaped to effect the opening and closing of

35 the press, means connected to the said second part for shifting the initial position of the

same and the initial position of said lever, and an actuator connected to the second part.

3. A pressing machine including in com-

35 bination cooperative pressing elements, one of which is movable toward and from the other; actuating mechanism for the movable

pressing element including a lever carrying a movable element; a second lever arranged

40 at an angle to the first lever; a cam on one of said levers; a cam follower on the other of said levers coacting with the cam; a shift-

45 able pivotal connection for the second lever; means for shifting said pivotal connection

50 to vary the starting position of the second lever and thereby adjust the pressure be-

tween the elements; and an actuator con-

55 nected to the second lever.

4. A pressing machine including cooper-

60 ating pressing elements, one of which is mov-

able toward and from the other, actuating mechanism for the movable element includ-

65 ing a lever carrying the movable element, a second lever arranged at an angle to the

70 first lever, the levers engaging directly with

75 each other and having coacting means where-

80 by movement of the second lever actuates the

able toward and from the other, actuating mechanism for the movable element includ-
ing a lever carrying the movable element, a second lever arranged at an angle to the first lever, the levers coacting directly with each other and having coacting means whereby movement of the second lever actuates the first lever to open and close the press, an actuator connected to the second lever, a carrier for the second lever, a pivotal connec-
tion between the second lever and the carrier, and means for shifting the carrier to shift the pivotal connection of the second lever and adjust the pressure delivered by the movable pressing element.

6. A pressing machine including cooper-
ating pressing elements, one of which is mov-
able toward and from the other, actuating mechanism for the movable element includ-
ing a lever carrying the movable element, a second lever arranged at an angle to the first lever, the levers having coacting means whereby movement of the second lever actuates the first lever to open and close the press and an actuator connected to the second lever, a pivoted carrier for the second lever, the carrier being in the form of an angle lever to one arm of which the second lever is pivoted and means coacting with the other arm to move the carrier on its pivot and thereby vary the pressure delivered by the movable pressing element.

7. A pressing machine including in com-
bination cooperative pressing elements, one of which is movable toward and from the other; actuating mechanism for the movable pressing element including a motion trans-
mitting member; an actuator connected to said motion transmitting member; a pivot-
ally mounted carrier in the form of an angle lever, the motion transmitting member be-
ing pivoted to one arm of the angle lever and tending to thrust the angle lever on its pivot-
al mounting during the final closing of the press; pressure resisting means connected to the other arm of the angle lever; and means for shifting the position of the pressure resisting means.

8. A pressing machine including cooper-
ating pressing elements, one of which is mov-
able toward and from the other, actuating mechanism for the movable element includ-
ing a motion transmitting member, an actuator connected to said member, a carrier in the form of an angle lever, the motion transmitting member being pivoted to one arm of the angle lever and tending to thrust the angle lever on its pivot during the final closing of the press, pressure resisting means connected to the other arm of the angle lever and manually controlled means for increasing the pressure exerted by the pressure re-
sisting means.

9. A pressing machine including cooper-
ating pressing elements, one of which is mov-

able toward and from the other, actuating mechanism for the movable element including a motion transmitting member, a fluid operated motor, connections between the motor and the motion transmitting member, a carrier for the motion transmitting member, the motion transmitting member tending to transmit motion in opposite directions to the movable element and to the carrier during the closing of the press, fluid operated means for resisting the movement of the carrier by the motion transmitting member and manually controlled means for increasing the pressure of said fluid operating means to shift the carrier and thereby boost the pressure delivered by the movable element.

10. A pressing machine including cooperating pressing elements, one of which is movable toward and from the other, actuating mechanism for the movable element including a motion transmitting member, a fluid operated motor, connections between the motor and the motion transmitting member, a carrier for the motion transmitting member, the motion transmitting member tending to transmit motion in opposite directions to the movable element and to the carrier during the closing of the press, means for resisting the movement of the carrier by the motion transmitting member and manually controlled means for increasing the pressure of the resisting means to shift the carrier to boost the pressure delivered by the movable element, and connections controlled by the movement of the movable member of the fluid operated motor for controlling the flow of fluid by said manually operated means, and manual means for controlling the flow of fluid to and from the motor.

11. A pressing machine including cooperating pressing elements, one of which is movable toward and from the other, actuating mechanism for the movable element including a motion transmitting member, an actuator connected to said member, a movable carrier for the motion transmitting member, the motion transmitting member acting to transmit motion in opposite directions to the movable element and to the carrier, means connected to the carrier for resisting movement thereof by the motion transmitting member, said resisting means including a cylinder having a piston therein connected to the carrier and manually operable means for controlling the flow of fluid under pressure to said resisting means to actuate the piston in the cylinder and shift the carrier.

12. A pressing machine including cooperating pressing elements, one of which is movable toward and from the other, actuating mechanism for the movable element including a motion transmitting member, a cylinder, a piston movable in the cylinder and connected to the motion transmitting member, a movable carrier for the motion

transmitting member, the motion transmitting member acting in opposite directions on the pressing element and the carrier, pressure resisting means including a cylinder having a piston movable therein connected to the carrier to resist movement thereof and also to move the carrier relatively to the motion transmitting member, the first cylinder having a port arranged to be uncovered by the piston therein when it approaches the limit of its out stroke, a pipe connecting the port and resisting means to boost the pressure in the cylinder of the resisting means, manually operated means for controlling the flow of motive fluid to and from the first cylinder and additional manually operated means for controlling the flow of additional air to the cylinder of the resisting means.

13. A pressing machine including cooperating pressing elements, one of which is movable toward and from the other, actuating mechanism for the movable element including a motion transmitting member, a cylinder, a piston movable in the cylinder and connected to the motion transmitting member, a carrier for the motion transmitting member, the motion transmitting member acting in opposite directions on the movable pressing element and the carrier, pressure resisting means including a cylinder having a piston movable therein connected to the carrier to resist movement thereof and also to shift the carrier relatively to the motion transmitting member, the first cylinder having a port arranged to be uncovered by the piston therein when it approaches the limit of its out stroke, a pipe connecting the port and the resisting means to boost the pressure in the cylinder of the resisting means, said pipe having a check valve therein, manually operated valves for controlling the flow of motive fluid to and from the first cylinder, automatic pressure operated means for holding the valves in their operated position when the press is closed, a manually operated valve for controlling the flow of additional air to the resisting means, the last mentioned valve having a valve casing connected in multiple with the pressure operated means for holding the former valves in their operated positions.

14. A pressing machine including cooperative pressing elements, one of which is movable toward and from the other; actuating mechanism for the movable element including motor means; means for adjusting the pressure delivered by the movable element; manually operated means for controlling the operation of the motor means to close the press; manually operated means for controlling the pressure adjusting means; and connections between the actuating mechanism and the manually operated pressure adjusting means whereby the operation of the last mentioned means is effective only after

the press is closed by the operation of the manually operated means which controls the closing of the press.

15. A pressing machine including a base, a buck mounted on the base, a head movable toward and from the buck to close and open the press, a lever carrying the head, said lever being pivoted between its ends to the base at the rear of the buck, actuating mechanism for the head including a motor and motion transmitting means connecting the motor with the head carrying lever in the rear of the buck, power operating means connected to the motion transmitting means for shifting a portion of the motion transmitting means to increase the pressure between the pressing elements; and means for holding said portion of the motion transmitting means shifted so that the increased pressure will be applied upon subsequent closing operations of the press.

16. A pressing machine comprising a frame, a buck mounted on the frame, a head movable toward and from the buck, a lever pivoted between its ends to the frame and carrying the head, said lever being provided with a cam on the rear arm thereof at the rear of the buck, a second lever pivoted to the frame and having a follower engaging with said cam, means for actuating the second lever, and means for shifting the pivot of the second lever to increase the pressure transmitted to the pressing elements upon actuation of the second lever.

35 In testimony whereof, I have hereunto signed my name, at Syracuse, in the County of Onondaga, and in the State of New York, this 17th day of Aug., 1928.

ERNEST DAVIS.
